UNITED STATES PATENT OFFICE.

HARRY F. PLUMMER, OF ALTOONA, PENNSYLVANIA.

RIVET-CUTTING TOOL FOR AIR-GUNS.

No. 806,493.

Specification of Letters Patent.

Patented Dec. 5, 1905.

Application filed May 31, 1905. Serial No. 263,073.

To all whom it may concern:

Be it known that I, HARRY F. PLUMMER, a citizen of the United States, residing at Altoona, in the county of Blair, State of Pennsylvania, have invented certain new and useful Improvements in Rivet-Cutting Tools for Air-Guns; and I do hereby declare the following to be a full, clear, and exact description of the invention, such as will enable others skilled in the art to which it appertains to make and use the same.

This invention relates to rivet-cutting tools such as are employed for cutting off the heads of rivets, the object of the invention being to provide a tool in the form of an attachment for substitution of the hammer that is used in connection with what is termed the "air-gun" in a pneumatic riveting-machine.

A further object of the invention is to provide a tool that will be cheap and simple of manufacture, that will permit of substitution of new blades when the old ones become worn, which will engage the rivet between the head and the surface against which it is formed, and with which the operation of cutting the rivets will be quickly effected.

Other objects and advantages of the invention will be understood from the following description.

30 In the drawings forming a portion of this specification, and in which like numerals of reference indicate similar parts in the several views, Figure 1 is a side elevation of the tool. Fig. 2 is a vertical section through the tool, 35 the section being continued through a rivet and the plates with which it is engaged and illustrating the operative positions of the cutting-blades. Fig. 3 is a bottom plan view of the tool.

40 Referring now to the drawings, there is shown a rivet-cutting tool comprising a casing including an upper cylindrical portion 5 and a base portion 6, which is contracted in one direction and broadened in a different direction at right angles, as illustrated. Formed longitudinally through the base 6 is a passage 7, which opens through the bottom of the base and which communicates at its upper portion with the opening 8 of the cylindrical 45 portion of the casing. Projecting inwardly from the side walls of the passage 7 are the guides, beads, or flanges 9, the lower faces of which are flush with the bottom of the casing.

50 Mounted slidably in the passage 7 are two cutting blades or members in the form of blocks 10 and 11, which rest upon the flanges 55

9 and the lower portions of which are narrowed and continued downwardly between said flanges, so as to lie flush with the bottom of the casing. The mutually-adjacent faces 60 of the blocks 10 and 11 are concaved, as illustrated, and these concaved faces form in connection with the bottom faces of the block the cutting edges 12 and 13, so that when the blocks are moved toward each other these 65 edges may engage and cut a rivet over which the base of the casing may be placed.

To urge the blocks 10 and 11 toward each other to perform the cutting operation, a plunger 14 is provided and is slidably mounted in the casing, the lower portion of the plunger comprising the spaced fingers 15 and 16, which are of a width equal to the narrowed portion of the casing, so as to slidably fit it and to permit of movement of the fingers 75 downwardly into the passage 7. The inner faces of the fingers 15 and 16 are beveled at their lower ends, as shown at 17 and 18, to engage the corresponding beveled sides 19 and 20, respectively, of recesses 21 and 22, 80 respectively, in the upper faces of the blocks 10 and 11, so that as the plunger is moved downwardly said blocks will be urged toward each other.

To limit the downward movement of the 85 plunger and the consequent inward movement of the cutting edges 12 and 13, a portion of the body of the plunger and the corresponding upper portion of the casing are enlarged, so that shoulders 25 and 26 are formed upon 90 the plunger and casing, respectively, which by contact limit the downward movement of the plunger.

In the sides of the base 6 and in the inner faces thereof are formed vertical channels 27, 95 that receive the legs of a U-shaped spring plate or bar 28, which are of a thickness somewhat greater than the depths of the channels, so that they lie partly in the path of movement of the blocks 10 and 11 from the passage 100 7, and thus prevent accidental displacement while permitting ready removal when desired.

A circumscribing groove 30 is formed in the outer face of the upper portion 5 of the casing to receive the usual retaining devices of the air-gun when the tool is attached, it being understood that the hammer or plunger of the air-gun engages the upper reduced end or stem 31 of the plunger 14 in the cutting operation. To prevent upward displacement of 105 the blocks 10 and 11, beads 32 are formed on the upper portions of the side faces of the pas-

sage 7 and engage in corresponding grooves in the side faces of the blocks.

The operation of the tool will be apparent from the above description and accompanying illustrations, it being understood that the tool is adjusted to receive the head of the rivet between the cutting-blades, or rather with the cutting edges close against the plate 34, against which the head of the rivet is made. The 10 plunger being then operated upon, the blades are forced toward each other with their cutting edges between the rivet-head and the blade 34, so as to engage the stem of the rivet and cut off the head.

15 What is claimed is—

1. A rivet-cutting tool comprising cutting members slidably mounted for movement toward and away from each other and a plunger constructed and arranged to urge the cutting 20 members toward each other.

2. A rivet-cutting tool comprising a casing having an open bottom, cutting members slidably mounted in the casing and having beveled portions and a plunger in the casing having beveled portions movable over the beveled portions of the cutting members, and under the influence of which the cutting members are movable toward each other.

3. A rivet-cutting tool comprising a casing 25 having an open bottom and inwardly-directed flanges, cutting members slidably mounted

upon the flanges and having cutting edges directed toward each other, said cutting members having recesses in their upper faces having beveled portions, and a plunger slidably mounted in the casing and comprising spaced fingers having beveled portions disposed to engage and move over the beveled portions of said recesses and under the influence of which the cutting members are movable toward each other.

4. A rivet-cutting tool comprising a casing having a transverse passage in its lower portion communicating with the upper portion of the casing, cutting-blocks slidably mounted in the transverse passage and having cutting edges directed toward each other, removable means for preventing movement of the cutting-blocks from the passage, said blocks having beveled portions, and a plunger mounted in the upper portion of the casing and having beveled portions arranged to engage the corresponding portions of the blocks and under the influence of which the blocks are movable toward each other.

55 In testimony whereof I affix my signature in presence of two witnesses.

HARRY F. PLUMMER.
